(57) **CLAIM**

The ornamental design for a decking element as shown and described.

DESCRIPTION

FIG. 1 is a front elevation view of a decking element showing our new design, the rear elevation view being a mirror image thereof;

FIG. 2 is a right side elevational view thereof;

FIG. 3 is a left side elevational view thereof;

FIG. 4 is a top plan view thereof; and,

FIG. 5 is a bottom plan view thereof.

The broken lines in the drawings illustrate portions of the decking element and form no part of the claimed design.

1 Claim, 5 Drawing Sheets
